Primary Examiner—Theodore M. Shooman*Assistant Examiner*—Philip Hyder*Attorney, Agent, or Firm*—Richard C. Litman[57] **CLAIM**

The ornamental design for a drywall utility knife handle, as shown and described.

DESCRIPTION

FIG. 1 is a front perspective view of the drywall utility knife handle;

FIG. 2 is a top plan view of the drywall utility knife handle;

FIG. 3 is a left side elevational view of the drywall utility knife handle;

FIG. 4 is a bottom plan view of the drywall utility knife handle;

FIG. 5 is a right side elevational view of the drywall utility knife handle;

FIG. 6 is a front view of the drywall utility knife handle; and,

FIG. 7 is a rear view of the drywall utility knife handle. The broken lines showing the hand in FIG. 1 and the knife blade in FIGS. 1-5 are for illustrative purposes only and form no part of the claimed design.

FIG. 1

FIG. 2
